MACHINE FOR PRESSING SOLES ON SHOE BOTTOMS

Sidney J. Finn, Beverly, Mass., assignor to United Shoe Machinery Corporation, Paterson, N. J., a corporation of New Jersey

Application October 25, 1937, Serial No. 170,732

48 Claims.

(Cl. 12—33)

This invention relates to machines for operating on shoes and is illustrated herein as embodied in a machine for use in pressing soles on shoe bottoms.

5 A large volume of the shoes manufactured today are of the so-called compo or cement type in which the outsole is attached to the shoe bottom by cement alone. In cement attaching a sole to a 10 shoe the sole must be positioned properly on the shoe bottom before pressure is applied to attach them permanently together. This sole positioning operation is sometimes performed by hand and sometimes by a cement sole attaching machine. The hand method is unsatisfactory because the position of the sole is dependent upon 15 the judgment of the workman and it is not at all certain that every shoe operated upon will have its outsole located in the proper position with respect to the shoe bottom.

20 With a cement sole attaching machine the positioning operation is satisfactory but it often involves complicated mechanism on the pressing pad and, in multiple machines, a duplication of parts which may increase the expense of the 25 machine considerably. Moreover, when the sole and shoe must be relatively positioned in the cement sole attaching machine before the sole attaching pressure can be applied, valuable time is consumed which might otherwise be used in 30 applying pressure, thereby speeding up the machine and increasing its production.

An important object of the present invention is to overcome the above disadvantages by providing an improved machine for relatively positioning a sole and shoe and for securing them together in such position prior to the cement sole attaching operation.

To the attainment of this object the invention provides in its broader aspect improved 40 means for positioning the sole relatively to the shoe which is accurate, rapid, and easy to operate, and it also provides improved means for pressing the sole and shoe together after they have been so positioned, these positioning and 45 pressing means being adapted for operating on both right and left shoes irrespective of the shapes of the curves in their shank portions and the various mechanisms being so arranged and timed in their operation that they release the 50 shoe as soon as it has been operated upon, thereby permitting shoes to be operated upon in rapid succession.

In accordance with one feature of the invention, the machine is provided with a sole and 55 shoe receiving pad having a fixed portion for

supporting the forepart of a shoe and a movable portion for applying pressure to the shank portion of the shoe. As illustrated, the movable portion is pivoted on the fixed portion and is swung toward the shoe by treadle operated means to apply pressure to the shank portion of the shoe, this treadle operated means preferably producing only sufficient pressure to conform the rear portion of the sole longitudinally to the shoe bottom and to stick the sole temporarily thereto. As illustrated, the treadle operated means is capable of swinging the movable portion of the pad a sufficient distance to permit it to operate on the shank portions of all types of shoes irrespective of their shapes.

In accordance with another feature of the invention, means is provided for supporting the rear portion of the shoe against pressure from the movable portion of the pad, said means being movable manually into operative position and returning by gravity to inoperative position as soon as pressure on the shoe is relieved, this shoe supporting means being locked against movement heightwise of the shoe when located in its operative position. As illustrated herein, the shoe support locking means is operated automatically by movement of the movable portion of the pad toward the shoe bottom, thereby insuring that the rear portion of the shoe will be supported before pressure is applied to the shank portion thereof. This locking means is also released automatically by return of the pad to its inoperative position.

Still another feature of the invention resides in the provision of improved positioning gages 35 constructed and arranged to engage the opposite edge faces of the heel portion of the sole and to position the sole relatively to the shoe bottom. As herein illustrated, the gages are actuated by spring means and are caused to position the sole 40 relatively to the shoe by movement of the shoe supporting means into operative position. The gages are located in a predetermined position relatively to the movable portion of the pad and are maintained in this position irrespective of 45 the position into which said movable portion is swung in applying pressure to the shank portion of the shoe. Means is also provided for locking the gages upon contact with the sole, said means being likewise permitted to operate automatically 50 by movement of the shoe supporting means into operative position.

A still further feature of the invention consists in the provision of additional gages for relatively positioning the sole and shoe on the pad, 55

said gages being capable of adjustment to adapt them for operating successively on right and left shoes. As illustrated, the adjustable gages are arranged to operate at the ball line of the shoe and are so constructed that the gages which operate on one of these members, for example the shoe, may be shifted transversely of the pad as a unit relatively to the sole gages to vary the amounts that the shoe gages overhang the sole gages at opposite sides of the shoe and thereby to determine the proper extension which the sole is to have relatively to the shoe bottom, this extension at the ball line usually being of a greater width at the outer side of the shoe than at the inner side so that, in right and left shoes, this greater extension is located at opposite sides of the pad. As illustrated, the mechanism for adjusting the gages consists of cams engaging means for actuating the ball line gages at both sides of the pad so that movement of the cams adjusts the shoe gages widthwise as a unit relatively to the sole gages without interfering with the actuating mechanism. Means is also provided for varying the amount of widthwise adjustment of the shoe gages for operating upon shoes having sole extensions of different widths.

The above and other objects and features of the invention, including novel details of construction and arrangements of parts, will now be described in connection with the accompanying drawings and will thereafter be pointed out in the claims.

In the drawings,

Fig. 1 is a side elevation of the machine embodying the present invention;

Fig. 2 is a side elevation of the upper portion of the machine on an enlarged scale with the parts shown in operative position;

Fig. 3 is an enlarged detail sectional view taken on the line III—III of Fig. 2;

Fig. 4 is a plan view of the pad and the sole and shoe locating means associated therewith, portions of the pad being broken away to show the construction more clearly;

Fig. 5 is a front elevation of the machine with the upper portion shown only in broken outline;

Fig. 6 is a plan view of the pad after the sole and shoe locating means have positioned a sole and shoe relatively to each other on the pad, only the operating ends of the forepart locating means being shown;

Fig. 7 is a transverse section on an enlarged scale taken on the line VII—VII of Fig. 1;

Fig. 8 is a side elevation, as viewed from the left in Fig. 7, of mechanism for adjusting the shoe and sole locating means relatively to each other for operating alternatively on right and left shoes;

Fig. 9 is a transverse sectional view through the forepart of the pad with a sole and shoe positioned thereon by the locating means;

Fig. 10 is a plan view of the right-hand, ball line sole and shoe locating means;

Fig. 11 is a rear elevation of the sole and shoe locating mechanism as viewed from the right in Fig. 10;

Fig. 12 is a front elevation, partly in section, of the sole and shoe locating mechanism;

Fig. 13 is a detail plan view of a lower portion of the locating mechanism, the view being sectioned on the line XIII—XIII of Fig. 12;

Fig. 14 is a vertical section of the locating mechanism taken on the line XIV—XIV of Fig. 10;

Fig. 15 is a plan view showing in detail a por-

tion of the heel positioning or gage mechanism of the machine;

Fig. 16 is a front elevation of the heel positioning mechanism as viewed from the left in Fig. 2;

Fig. 17 is a side elevation of the heel positioning mechanism, as viewed from the right in Fig. 15;

Fig. 18 is a vertical section of the heel positioning mechanism taken on the line XVIII—XVIII of Fig. 15;

Figs. 19 and 20 are detail sectional views of portions of the heel positioning mechanism taken respectively on the lines XIX—XIX and XX—XX of Fig. 17; and

Fig. 21 is a fragmentary elevational view of a part of the heel gage mechanism shown in Fig. 15.

The machine is provided with a base 30 from which extend two upright walls 32, 34 (Figs. 1 and 5) connected at their upper ends by a horizontal plate 36 to which is bolted a frame member 38 comprising a single upstanding wall located substantially centrally of the walls 32, 34. The frame 38 curves forwardly and has secured to its upper end, at an angle of substantially 45° to the horizontal, a transverse plate 40 of substantial width to which is secured by screws 42 (Fig. 2) a fixed pad supporting table or plate 44 carrying a yieldable pad 46 preferably of solid rubber. The pad supporting plate is formed in two sections, a movable section 48 being pivotally connected to the forward end of the fixed section 44 by pins 50 (Figs. 1 and 4) and being arranged to underlie the shank portions of a sole and shoe, the stationary section 44 underlying the foreparts of the sole and shoe. As shown in Fig. 1, the movable portion of the pad supported by the pivoted section 48 of the support normally lies in the same plane as the fixed portion of the pad supported by the section 44, but the section 48 may be swung upwardly above its pivots 50 to bring a sole and the movable shank portion of the pad into engagement with the shank portion of a shoe after the shoe has been clamped against heightwise movement relatively to the pad, as shown in Fig. 2.

The stationary section 44 of the pad support carries a plurality of sets of sole and shoe locating means including gages arranged to be moved simultaneously toward a sole placed on the pad by an operator, the gages being arranged to find the edge face of the sole and then to become locked so that the shoe gages on the several sets will be located in predetermined positions relatively to the edge face of the sole and will locate the shoe in the desired relation thereto. Two sets of sole and shoe gage mechanisms are located at acute angles to the longitudinal median line of the pad near its inner or toe end, as viewed from the front, these sets being arranged to engage a sole and shoe in the vicinity of the tip line and being indicated generally in the drawings by the numerals 52, 53 (Fig. 4). The other two sets of gage mechanisms, indicated generally in Fig. 4 by the numerals 56 and 58, are located near the outer end of the stationary support 44 and are arranged to move inwardly substantially at right angles to the edge face of the sole in the vicinity of its ball line.

The four sets of positioning gages are actuated simultaneously by mechanism located at opposite sides of the frame 38 and connected, in a manner to be hereinafter described, to a treadle 58 (Fig. 1) pivoted on a shaft 60 located near

75

the base of the machine. All four sets of positioning mechanisms are similar in construction except that the tip line mechanisms are somewhat simpler than those at the ball line. The description of the ball line gage mechanisms will be confined to the right-hand set 56 shown in Fig. 4, it being understood that the opposite set 58 is of substantially the same construction. The tip line gage mechanism 52 will then be described with reference to similar or corresponding parts of the ball line gage mechanism 56, it being understood in this case also that the opposite tip line gage mechanism 54 is identical with the set 52.

The fixed pad support 44 is provided with four rectangular projections or blocks 60 (Figs. 6 and 7) two of which are located at the inner or toe end of the support and the other two of which are located substantially opposite the ball or break line of a shoe on the pad. These blocks 60 confine the forepart of the pad on the fixed support 44, the pad being held against sliding forwardly on the support by upstanding projections or blocks 62 formed on the pivoted section 48. The blocks 62 provide bearings for the pivot pins 50 and fit into recesses in the outer or shank portion of the pad, which portion is somewhat narrower than the forepart.

Secured to the upper side of the block 60 which supports the right-hand ball line gage mechanism is a transverse plate 64 (Figs. 7, 12 and 14) which overlaps the pad slightly and also extends outwardly of the support beyond the block 60. The plate 64 is provided with a central shouldered opening 66 (Fig. 14) and secured by screws to the upper surface of the plate are relatively thin plates 68, 70 the inner edges of which overlie the opening 66 and form a T-shaped slot. The plate 70 has an upwardly extending wall 72 at its inner edge having a flat upper surface 74.

Mounted for sliding movement in the T-slot in the plate 64 is a slide member 76 the left-hand end 78 of which (Figs. 10 and 12) is reduced in width and extends downwardly toward the pad to form the sole gage member for finding the edge face of a sole placed on the pad. The other end of the slide 76 is pivotally connected by a pin 80 (Figs. 10 and 11) to the upper end of a substantially vertical lever 82 pivoted on a shaft 84 mounted in ears 86 extending outwardly from a block formed on the lower side of the pad support 44. The lever 82 extends downwardly below the pivot 84 and at its lower end is provided with a horizontal boss 88 (Figs. 11 and 13) to the forward side of which, as viewed in Fig. 12, is pivotally secured by a pin 90 a casting 92. The casting 92 has a forward cylindrical portion extending at right angles to the boss 88 and surrounding a horizontal shaft 96, this portion forming a bearing for a bushing 94 which is rotatable in the casting and is connected to the shaft 96 by a key 98 (Figs. 11 and 12). The shaft 96, as best shown in Fig. 7, is supported for limited movement heightwise of the pad in a slot 100 formed in an arm 102 projecting downwardly from the forward end of the pad support 44, the shaft being held against sliding movement widthwise of the pad by collars 104 secured to the shaft and bearing against opposite sides of the arm 102.

At its outer or right-hand end, as viewed in Fig. 12, the bushing 94 is enlarged and has a cam 106 formed thereon the purpose of which will be explained hereinafter. The upper portion of the lever 82 is provided with a laterally

and downwardly projecting arm 108, the outer end 110 of which is bent at right angles to the arm, as shown in Figs. 10 and 11. Pivotal movement of the lever 82 around the shaft 84 will slide the sole gage 78 in the plate 64 toward and from the edge face of a sole on the pad.

The slide member or gage 76, 78 has a U-shaped slot (Fig. 14) in its upper side in which is slidably mounted a member 112 which, in turn, has a slot 114 formed therein. Adjustably mounted in the slot 114 is a shoe gage 116 the inner or shoe engaging end of which is enlarged and projects upwardly, as shown in Fig. 12. The shoe gage 116 is confined in the slot 114 by a cover plate 118 secured by screws 120 to the slide member 112, the screws passing through a slot 122 (Fig. 10) in the shoe gage 116 to permit lengthwise adjustment of the latter relatively to the slide 112. The above arrangement permits the shoe gage to be adjusted laterally of the pad relatively to the sole gage 78.

The means for adjusting the shoe gage relatively to the sole gage is eccentric mechanism, indicated generally in Figs. 10 to 12, inclusive, by the reference numeral 124, and substantially the same in construction and operation as the gage adjusting mechanism disclosed in Letters Patent of the United States No. 2,047,185, granted July 14, 1936, on an application filed in the names of Milton H. Ballard et al., this mechanism comprising, briefly, a frusto-conical member rotatably mounted in the plate 118 and having an eccentric pin 126 (Fig. 10) projecting downwardly into a transverse slot in the shoe gage 116 whereby, when the frusto-conical member is rotated, the shoe gage is moved longitudinally relatively to the slide 112 and the sole gage 78. A handle 128 is provided for rotating the adjusting mechanism and a relatively heavy compression spring (not shown) maintains the mechanism in any position into which it may be adjusted.

The right-hand portion of the slide 112 is provided with an outwardly extending ear 130 (Fig. 10) whereby the slide is pivotally connected by a screw 132 to a lever 134 pivotally mounted on the shaft 84 and having a downwardly curved arm 136 the lower end of which is rounded and bears against the cam 106 previously referred to. The cam 106 is for the purpose of effecting an adjustment of the ball line shoe gage relatively to its sole gage to enable the ball line gage mechanism to operate successively on right and left shoes the sole extensions of which, at the ball line, are usually greater at the outer side of the shoe than at the inner side and which extensions, of course, in right and left shoes are located at opposite sides of the pad. Another cam 106 is provided at the opposite side of the pad for accomplishing the same adjustment on the left-hand ball line gages, as will be more fully explained hereinafter.

The arm 136 is caused to bear against the cam 106 by the following arrangement. The hub of the lever 82, as shown in Fig. 11, extends toward and engages the lever 134 thereby spacing these levers from each other lengthwise of the pad and providing a bearing for a relatively strong torsion spring 138 one end of which bears against the support 44 and the other end of which hooks around the lever 82, thereby tending constantly to swing this lever in a counterclockwise direction, as viewed in Fig. 12, to move the sole gage 78 inwardly toward the longitudinal median line of the pad. It will be seen from the above that the lower arm of the lever 82, which carries the

casting 92 and cam 106, is thus urged constantly in a right-hand direction, as viewed in Fig. 12.

The lever 82 is provided with a second projection or lug 140 (best shown in Figs. 11 and 12) 5 extending at right angles to the arm 108 and the lever 134 is likewise provided with a lug 142 which is in alignment with the lug 140. Both lugs are provided with pins which support a compression spring 144 tending to urge the levers 82 and 134 10 in opposite directions, as viewed in Fig. 12, and thereby to keep them separated radially of the shaft 84 as much as is permitted by the associated mechanism. Consequently, the lever 82, when located in its inoperative position, as shown 15 in Fig. 12 (which position is determined by other mechanism later to be described), is maintained in this inoperative position against the force of the torsion spring 138 which is tending to urge it in a counterclockwise direction into operative position. The compression spring 144 bears 20 against the lug 140 which, in effect, is fixed relatively to the lug 142 and which, through the lug 142, forces the lever 134 in a clockwise direction to keep the two levers separated radially and 25 also to hold the rounded end of the arm 136 against the cam 106.

Pivottally mounted on the shaft 84, rearwardly of the levers 134 and 82, as viewed in Fig. 12, is a third lever 146 which has pivotally connected to its upper end by a pin 148 a link 150 30 extending toward the pad and connected at its inner end by a screw 152 to the lower end of an arm 154 the upper end of which is in the form of a cylindrical boss 156 rotatably mounted on 35 a shoulder screw 158 (Fig. 14). The screw 158 is threaded into an upstanding projection 160 on the rear portion of the slide 76 and the boss 156 is eccentric relatively to the screw so that when the arm 154 is swung in a clockwise direction, 40 as viewed in Fig. 12, the eccentric portion of the boss will jam against the surface 74 previously referred to, thereby locking the slide 76, and the sole gage 78 and shoe gage 116 carried thereby, against movement away from a sole on the pad.

The lever 146 has a plate 162 secured thereto which extends outwardly and downwardly in line with the arm 108 on the sole gage lever 82. This plate has a cylindrical lower portion 164 surrounded by a compression spring 166 the outer 50 end of which bears against the right-angle projection 110 on the arm 108. When the mechanism is in its inoperative position, as shown in Figs. 10 and 12, the end of the cylindrical portion 164 of the plate engages the projection 110 and the spring 166 is compressed, this spring 55 being weaker than the torsion spring 138 or the compression spring 144.

The gage operating levers 134 and 82 and the lock operating lever 146 are normally held in 60 their inoperative positions, by mechanism presently to be described, against the force of the torsion spring 138, thereby maintaining the sole and shoe gages in their open or retracted positions. When the mechanism holding these levers 65 in inoperative position is released the torsion spring 138 forces the sole gage lever 82 in a counterclockwise direction, as viewed in Fig. 12, to move the sole gage 78 yieldingly toward the edge face of a sole on the pad. Since the lever 134 is connected positively to the sole gage lever 82 for movement toward the sole by the arm 136 bearing against the cam 106, the lever 134 moves 70 inwardly toward the sole yieldingly with the lever 82, the spring 144 keeping the arm 136 against 75 the cam and thus holding the two levers sepa-

rated. In other words, the levers 82 and 134 are maintained in the same relation to each other when they swing inwardly about the shaft 84 to move the gages toward a sole as when they are located in their inoperative positions shown in Fig. 12, so that the sole and shoe gages remain in predetermined positions relatively to each other when they operate on a sole and shoe. Moreover, the compression spring 144 cannot yield to cause this position to change when a shoe is placed upon the sole on the pad because the shoe gage lever 134 is held positively against movement away from the sole by the cam 106. As stated above, the shaft 96 is arranged for limited movement heightwise of the pad in the arm 102 to allow for the swing of the lower arm 15 of the lever 82.

As the levers 82 and 134 are swung inwardly as a unit about the shaft 84 to move the gages toward a sole on the pad, the lock controlling 20 or operating lever 146 is also swung about this shaft in a counterclockwise direction, as viewed in Fig. 12, by reason of the positive engagement of the cylindrical end 164 of the plate 162 with the projection 110 on the arm 108 of the sole 25 gage lever 82. Accordingly, when the gage mechanism is permitted to operate the three levers swing initially as a unit about the shaft 84 under the yielding force of the torsion spring 138 until the sole gage 78 finds the edge face of a sole 30 on the pad.

During this movement of the gages toward the sole the link 150 on the lock operating lever 146 does not rotate the arm 154 about the screw 158 because the latter, being mounted on the slide 35 portion 76 of the sole gage 78, has moved inwardly toward the sole with the rest of the mechanism. When, however, the sole gage contacts with the edge face of the sole, the movement of the sole gage lever 82 and the shoe gage lever 134 stops. At this time the relatively light compression spring 166 between the arm 108 and the plate 162 expands and causes the lock operating lever 146 to continue its swinging movement in a counterclockwise direction, as viewed in Fig. 12, 40 about the shaft 84. This movement causes the link 150 to rotate the eccentric 156 about the pin 158 until it jams against the surface 74 and thus locks the entire gage mechanism positively against outward movement away from the edge face of 50 the sole. In other words, the sole and shoe gages 78, 116 are moved inwardly yieldingly toward the sole on the pad by the torsion spring 138 and, upon contact of the sole gage with the edge face of the sole, the locking mechanism is operated by 55 the light spring 166 to lock the gages in their operative position. Reverse movement of the sole and shoe gage levers 82, 134 and the locking lever 146 unlocks the gages and returns them to their inoperative positions, this movement being 60 accomplished by the gage actuating means referred to above which acts directly on the gage locking lever 146, as will be hereinafter explained. Before describing how the gages are unlocked and retracted, the right-hand tip line sole and shoe 65 positioning mechanism will be described and also the mechanism for operating both right-hand sets of gage mechanisms and for simultaneously operating the left-hand sets of gage mechanisms.

Referring to Figs. 2 and 4, it will be seen that 70 the right-hand tip line sole and shoe positioning mechanism comprises a sole gage 168 and a shoe gage 170 carried, respectively, by slide members 172 and 174 mounted for longitudinal sliding movement in a plate 176 secured to a rear block 75

60 and provided with a T-slot 178, the sole and shoe gages being adjustable relatively to each other by eccentric mechanism the same as that for adjusting the ball line gages, this mechanism being indicated generally in Fig. 4 by the numeral 180. The proportions and shapes of the tip line gages 168, 170 are somewhat different from the ball line gages 78, 116 but their construction and operation are substantially the same. The pad 5 supporting plate 44 carries a pair of downwardly projecting ears 184 (Fig. 2) in which is mounted a shaft 186. The tip line shoe gages do not have to be initially adjusted relatively to the sole gages to adapt them for operating successively on right 10 and left shoes, because the extension of the out-sole beyond the shoe upper in the vicinity of the tip line of either a right or a left shoe is substantially the same at both sides of the shoe. Accordingly, no mechanism for effecting such an 15 adjustment is provided for the tip line gages. The sole and shoe gages 168, 170 are moved inwardly toward the sole by a torsion spring (not shown), similar to the spring 138, operating on a sole gage operating lever 188 (Fig. 4) pivoted on the shaft 186 and connected directly to the sole gage slide 174. When the gage actuating mechanism which 20 normally holds the gages away from the sole is operated, the tip line sole and shoe gages move inwardly as a unit until the sole gage 168 finds the edge face of the sole, thereby positioning the 25 shoe gage 170 for receiving the shoe and locating the shoe relatively to the sole. The lever 188 is provided with a downwardly extending arm 190 similar to the arm 108 having a right angle projection 192 thereon which engages the lower end 30 of a plate 194 secured to a lock operating lever 196 and having a light compression spring 195 around its lower portion engaging the projection 192. The lever 196 is mounted on the shaft 186 and is connected at its upper end by a link 198 to eccentric locking mechanism, indicated generally 35 in Fig. 4 by the numeral 200, and similar in construction to that on the ball line gage mechanism 58. The tip line gages are moved yieldingly as 40 a unit toward the sole until the sole gage 168 finds the sole and then the lock operating lever 196 is 45 swung forwardly by the spring 195, as described above, to operate the locking mechanism 200 and lock the tip line gages in operative position.

50 The ball line lock operating lever 146 and the tip line lever 196 are provided respectively at their lower ends with outwardly projecting arms 202 and 204 (Figs. 2 and 12). Pivots connected to the arms 202, 204 are downwardly extending rods 206, 208 carrying lock nuts 210, 212 on their lower ends. These rods 206, 208 extend loosely through laterally extending arms 214, 216 on the upper end of an angle bar 218 (Figs. 2 and 7). The ball line and tip line gage mechanisms at 55 the opposite or left-hand side of the pad are likewise connected by downwardly extending rods to similar laterally extending arms 220 and 222 (Figs. 4 and 7) on the upper end of another angle bar 224. These angle bars which, in plan view (Fig. 4), form a so-called spider arrangement, are secured to each other for movement heightwise of the pad at opposite sides of a thick portion 226 (Fig. 7) of the frame 38 through a slot 228 extending heightwise thereof. The bars 60 are secured together for heightwise movement in the slot 228 by spacing rolls 230 which have a sliding fit in the slot and have reduced end portions upon which the angle bars are fastened by nuts 232. When the spider member is moved 65 downwardly away from the pad the arms engage

the lock nuts 210, 212 on the rods and swing the lock operating levers 146, 196, outwardly away from the pad. When, on the other hand, the spider member is moved upwardly relatively to the pad, thereby freeing the rods 206, 208, the torsion springs on the gage mechanisms move the sole and shoe gages on all of the mechanisms simultaneously toward the sole. 5

The angle bar 218 of the spider member has pivotally secured to it by a screw 234 a curved link 236 (Figs. 1, 2 and 7) the lower end of which is pivotally secured by a pin 238 to the rear arm of a bell crank lever 240 pivoted on the frame 38 on a stud 242. A forward arm 244 of the bell crank lever 240 carries a pin 246 which extends through a slot 248 formed in the lower portion of a link 250 (Figs. 1 and 2) extending forwardly and downwardly and being pivotally secured at its upper end by a screw 252 to a forward arm 254 of a three-armed, yoked lever 256 straddling the frame 38 and pivoted thereon by a pin 253. The arm 244 of the bell crank lever has a tension spring 260 hooked to its upper end, the other end of the spring being secured to the lower end of the link 250. The pin 246 is normally held at 25 the lower end of the slot 248 by the spring 260, as shown in Fig. 1, the pin being permitted by the spring to move along the slot when the mechanism is operated.

The yoked lever 256 has a rearwardly extending arm 262 to which is pivotally secured by a pin 264 an upwardly and forwardly inclined rod 266 pivotally secured at its upper end by a pin 268 to the rear end of shoe engaging member or presser foot 270. The presser foot 270 is pivoted between ears 272 on the frame 38 on a pin 274 and it has a forwardly extending arm 276 the end of which is curved downwardly and is provided with a toe rest or pad 280 adapted to engage and press the forepart of the shoe against 40 the sole and pad. Counterclockwise movement of the lever 256, as viewed in Fig. 1, swings the forepart presser foot 270 about the pivot 274 to move the toe rest 280 into engagement with the shoe. 45

The lever 256 is provided with a third arm 282 extending forwardly at the left-hand side of the frame and pivotally connected by a pin 284 to a treadle rod 286 which, at its lower end, is connected by a pin 288 (Fig. 1) to the gage operating treadle 58. 50

The operation of the mechanism just described in elevating the spider member and permitting the torsion springs to move each set of gages inwardly to find the edge face of the sole on the 55 pad is as follows: Depression of the treadle 58 swings the yoked lever 256 in a counterclockwise direction, as viewed in Fig. 1, thereby swinging the presser foot 270 in the same direction about its pivot 274 to move the toe rest 280 toward the 60 shoe. It is desired, however, that the gage mechanisms be operated to move the sole gages into contact with the edge face of the sole and to lock all the gages in operative position before the shoe is mounted on the sole and before the presser 65 foot 270 has moved fully into operative position. Accordingly, movement of the lever 256, while moving the presser foot partly toward the pad, also moves the arm 254 and link 250 downwardly. During the first part of the movement of the link 70 250 the pin 246 is maintained by the spring 260 at the lower end of the slot 248 so that the bell crank lever 240 is rotated in a counterclockwise direction to elevate the curved link 236 and raise the four arms forming the spider member away from 75

engagement with the lock nuts on the opposite pairs of rods 206, 208 connected to the lock operating levers of the gage mechanisms. Consequently, this initial depression of the treadle permits the four sets of gages to be moved simultaneously by their torsion springs toward the center of the pad until the sole gages find and contact yieldingly with the edge face of the sole, the gages thereupon being locked by continued movement of the lock operating levers 146, 196 in the manner already described.

Further depression of the treadle 58 stretches the spring 260 through continued lowering of the link 250 and permits the pin 246 to ride along the slot 248 without further movement of the bell crank lever 240 but maintaining the spider member in its elevated position relatively to the lock nuts on the rods 206, 208. This further depression of the treadle also completes the operative movement of the presser foot 270 to bring the latter into operative engagement with the forepart of a shoe which will, in the meantime, have been introduced on the pad by the operator in the position determined by the shoe gages.

In order that the operator may remove his foot from the treadle 58 after the gages have become locked so that he may introduce the shoe, and also so that he may thereafter depress another treadle with which the machine is provided for applying pressure to the shank portion of the shoe, means is provided for locking the treadle 58 in any position into which it is depressed. The elevated position of the treadle 58 is determined by a stop plate 290 (Figs. 1 and 5) bolted to the lower portion of the wall 34 and provided with a rearwardly extending projection 291 arranged to engage the top of a pawl 292 pivotally secured by a screw 294 to the treadle 58. The pawl engages ratchet teeth 296 formed on a vertical edge of the stop plate 290 so that when the treadle is depressed the pawl will lock the treadle in any position into which it may be depressed. The pawl 292 is constantly urged into engagement with the ratchet teeth by a rod 298 pivotally secured at one end to the pawl and at its other end to the lower arm of a pawl release lever 300 pivoted on the treadle by a pin 302 and extending forwardly in position to be engaged by the operator's foot. The rod 298 is normally urged forwardly by a spring 306 secured to a collar on the rod and to the treadle 58. Stepping on the lever 300 forces the rod 298 rearwardly and swings the pawl away from the ratchet teeth thereby releasing the treadle 58. The treadle is normally maintained at the upper limit of its swinging movement by a heavy tension spring 308 (Fig. 5) extending between the treadle and a pin 310 in the frame.

When the treadle 58 is unlocked in the manner just described, the yoked lever 256 is swung in a clockwise direction, as viewed in Fig. 1, to swing the forepart presser foot 270 into its inoperative position and to cause the spider member to pull downwardly upon the rods 206, 208, first to unlock the gage mechanisms and then to withdraw the sole and shoe gages into their inoperative positions. The action of the several levers associated with each gage mechanism during this retracting movement is as follows: The lock operating levers 146, 196 of the ball and tip line gage mechanisms, for example at the right-hand side of the pad, are swung outwardly or in a clockwise direction, as viewed in Figs. 4, 7 and 12, and the relatively light compression springs 166, 195 thereon are compressed until

the plates 162, 194 contact with the projections 110, 192 on the sole gage levers 82 and 188. Thereupon the sole gage levers are swung positively in a clockwise direction about their supporting shafts against the torsion springs 138 5 which actuate the gage mechanisms. The cams 106 carried by the two ball line gage mechanisms are moved inwardly toward the pad as the upper ends of the sole gage levers swing outwardly. This permits the shoe gage levers 134 10 of these ball line gage mechanisms to be swung outwardly with the sole gage levers through the connection of the spacing springs 144 which, as stated above, constantly hold the lower arms 136 of the levers 134 in contact with the cams 15 106. Accordingly, the sole and shoe gages at both sides of the ball line will move simultaneously away from the sole and shoe into retracted position and the respective positions of the gage levers and the lock operating levers relatively to each other will be maintained except that the lock operating levers 146 will first move relatively to the other two levers of each set until the plates 162 contact with the projections 110. The movement of the tip line gages into retracted position 25 is accomplished in substantially the same manner, the light springs 195 first compressing to unlock the gages and thereafter the gage operating levers 188 operating positively to retract both the sole and the shoe gages from the tip 30 line of the shoe.

As indicated above, the purpose of the cams 106 is to effect a simultaneous widthwise adjustment of both shoe gages 116 at the ball line relatively to their sole gages 78 to adapt the ball line 35 gage mechanisms for operating successively on right and left shoes, this adjustment being required because the amount of the sole extension beyond the upper at the outer side of a shoe is usually considerably greater than the extension 40 at the inner side of the shoe at the ball line. It will be seen, therefore, that when operating successively on right and left shoes, the ball line shoe gages should be capable of adjustment preferably as a unit widthwise of the pad relatively 45 to the sole gages so that the amount that the shoe gage overhangs the sole gage at the side of the pad corresponding to the outer side of either a right or a left shoe is considerably 50 greater than the amount of this overhang at the opposite side of the pad and so that this variation in the gages can be readily shifted from one set of ball line gages to the other.

In addition to adjusting the shoe gages simultaneously widthwise of the pad relatively to the sole gages to get a greater overhang of the shoe gage at the proper side of the pad for the shoe being operated upon, it is also desirable to vary this overhang of the shoe gage relatively to the sole gage for different types of shoes. For example, one type of shoe might have a sole extension at the outer side of the ball line which is one-quarter of an inch while the extension at the inner side might be seven thirty-seconds of 65 an inch or less. This would, of course, be true of both the right and left shoes of that pair. On another type of shoe, however, the sole extension at the outer side of the ball line portion might be greater than indicated above and at 70 the inner side it might be considerably less. Consequently, in addition to providing means for effecting a quick and simultaneous adjustment of the shoe gages for right and left shoes, provision is also made for varying the amount 75

of adjustment to accommodate shoes having different sole extensions.

The cams 106 operating on the arms 136 of the shoe gage levers 134 accomplish the simultaneous adjustment of the shoe gages for right and left shoes and they also determine the amount of widthwise variation between the shoe and sole gages for different types of shoes. The left-hand cam 106, as viewed in Fig. 7, is carried by a casting 312 secured to the lower arm of the lever 82 and having a cylindrical portion surrounding the shaft 96 in the same manner as the right-hand cam 106 described above, the cam itself being formed on the end of a bushing rotatable in the casting 312 and keyed to the shaft 96. The casting 312 has a laterally extending portion 314 provided at its outer end with an upstanding lug 316 also surrounding the shaft 96. Fastened by a screw 318 to the lug 316 is a circular plate 320 (Figs. 7 and 8) through which the shaft 96 passes and rotatably mounted on the shaft in front of the plate 320 is a U-shaped member having a relatively long inner arm 322 and a shorter outer arm 324 to which is secured a rod 326 having a hand nut 328 threaded on its upper end. Mounted on the rod below the hand nut 328 is a sliding block or collar 330 having an inner projection 332 extending into a slot 334 (Fig. 8) extending lengthwise of the long arm 322. A spring 336 on the rod 326 between the arm 324 and the collar 330 holds the collar against the nut 328.

Rotatably mounted on the shaft 96 at opposite sides of the shorter arm 324 are lower links 338, 340 of a lazy tong arrangement, these links having pivotally secured to their upper ends by pins 342, 344, another pair of links 346, 348 completing the lazy tongs. The upper links 346, 348 are pivotally connected by a screw 350 to the sliding collar 330. The shaft 96 extends laterally beyond the outer link 340 and is provided on its outer end with a fixed collar 352 between which and the link 340 is a compression spring 354, this spring being strong enough to hold the mechanism by friction against the plate 320 in any position on the shaft into which it may be swung. The plate 320 is provided at its right, as viewed in Fig. 8, with a stop pin 356 which, as the parts are shown in that figure, is engaged by the lower link 338 of the lazy tong arrangement but which, when the mechanism is swung in a counterclockwise direction about the axis 96, as hereinafter described, is long enough to be also engaged by the lower link 340.

When it is desired to move the ball line shoe gages 116 relatively to the sole gages 78 to shift the larger overhang of the shoe gage relatively to the sole gage from one side of the pad to the other, for operating successively on right and left shoes having the same sole extensions on their outer sides but at opposite sides of the pad, the hand nut 328 is grasped and the entire assembly is swung in a counterclockwise direction relatively to the plate 320 and about the axis 96 from the position shown in Figs. 7 and 8 to a position in which the lower link 340 contacts with the stop pin 356, the compression spring 354 acting to hold the mechanism in this latter position against accidental rotation relatively to the plate 320. When the mechanism is swung about the axis 96, as just described, the lazy tongs and nut 328 will extend downwardly and slightly toward the right radially of the shaft 96, as viewed in Fig. 8. Since the arm 324 is keyed to the shaft 96, the shaft is rotated in its bearing 102

to turn the bushings in the castings 92 and 312, which are likewise keyed to the shaft, thereby rotating the cams 106 a distance such that the cam surfaces thereon will shift the greater overhang of one shoe gage 116, for example, the right-hand shoe gage in Fig. 7, over to the left-hand shoe gage and simultaneously to shift the right-hand shoe gage into the retracted position originally occupied by the left-hand shoe gage. In this way a quick adjustment is obtained for operating successively on right and left shoes.

When it is desired to vary the amount of the overhang of the shoe gages relatively to the sole gages, the hand nut 328 is turned on the threaded stem 326 to raise or lower the nut and thereby to open or close the lazy tongs and thus to change the initial position of the stem 326 and the rest of the assembly radially of the axis 96 and relatively to the pin 356 in the plate 320. Adjusting the nut 328 heightwise of the stem 326, of course, turns the shaft 96 and the cams 106 into a different initial position so that the relative positions of the sole and shoe gages laterally of the pad are likewise changed. Moreover, when the stem and lazy tong mechanism is swung in a counterclockwise direction about the axis 96 to effect the adjustment, as described above, the stopping position of the link 340 against the stop pin 356 will be such that the shoe gages will be shifted amounts determined by the adjusted positions of the lazy tongs.

During the positioning of the foreparts of the sole and shoe and the clamping of these portions against the forepart of the pad 46, the movable section 48 of the pad support is located in the same plane as the fixed section 44, that is, at an angle of substantially 45° to the horizontal, as shown in Fig. 1. The shank and heel portions of the sole, therefore, except in the case of a conformed or premolded sole, will lie flat against the shank portion of the pad with the heel portion of the sole projecting forwardly beyond the end of the pad. Means is provided for finding and gripping the projecting heel portion of the sole and for positioning it widthwise with respect to the heel portion of the shoe while the sole is still flat on the pad with its shank and heel portions spaced from corresponding portions of the shoe bottom. After the shank and heel portions of the sole and shoe have been properly aligned with each other, the movable section 48 of the pad support is swung upwardly toward the shoe to press the sole into engagement therewith. Before this occurs, however, mechanism associated with the heel positioning mechanism is operated to engage the last in the shoe and to support the rear portion of the shoe against pressure from the shank portion of the pad, this mechanism being locked against movement heightwise of the shoe when located in operative position.

The mechanism for relatively positioning the shank and heel portions of the sole and shoe is best illustrated in Figs. 1, 2 and 15 to 21, inclusive. The frame 38 is provided at its forward edge some distance below the pad with a boss 358 (Figs. 1 and 2) in which is secured substantially at right angles to the plane of the pad and approximately under the ball line of a shoe mounted thereon an upwardly projecting stud 360. Rotatably mounted on this stud is a casting 362 having upwardly projecting ears 363 which support a horizontal shaft 364 extending widthwise of the machine. Fulcrumed on the shaft 364 near its central portion is a lever 366 which extends forwardly and has an upwardly project-

ing arm 368 the upper end of which is wide and flat and engages a rounded projection 370 on the under side of the movable section 48 of the pad support. The lever 366 normally supports the section 48 in the position shown in Fig. 1 and is arranged, in a manner to be hereinafter described, to swing this section upwardly toward the shoe to bring the sole into engagement therewith and to conform the sole and pad to the shape of the shoe bottom. A tension spring 372 connected to a lower portion of the lever and to a pin in the rounded projection 370 maintains the projection in engagement with the arm 368 while permitting the projection to slide along the flat surface thereon during swinging movement of the section 48.

The lever 366 has a lower arm 374 which has pivoted thereto on a pin 376 a forwardly and upwardly extending arm 378 of considerable width, as shown in Fig. 5, and having an upper portion 380 which supports the mechanism for engaging the heel portion of the sole and positioning it and the shank portion of the sole relatively to the shoe bottom. This heel positioning or gage mechanism is located in a predetermined position heightwise relatively to the movable section 48 of the pad support and, since it is pivotally connected to the lever 366 which supports this movable section, always remains in this predetermined position, although it may, if desired, be adjusted heightwise relatively to the support 48 to accommodate different types of soles, for example, conformed or premolded soles. Before explaining how the heel gage mechanism acts to position the heel and shank portions of the sole relatively to the shoe bottom, which operation takes place in conjunction with the movement into its operative position of the means referred to for supporting the heel portion of the shoe against pressure from the pad, the construction of the gage mechanism itself and its operation in engaging and gripping the heel end of the sole will be explained.

Referring to Figs. 15 to 21, inclusive, the upper end 380 of the gage supporting lever 378 is provided with a transverse slot 382 (Figs. 17 and 18) in which are slidably mounted heel gages 384, 386. The gage 384 comprises a slide portion 388 mounted in the slot 382 and having an upwardly projecting portion 390 the upper end of which forms the gage proper, the latter comprising a lower ledge or lip 392 (Fig. 16) of considerable length projecting inwardly over the pad, and an upper and shorter inwardly projecting lip 394 arranged to overlie the sole when a sole edge engaging surface 396 on the gage finds the edge face of the sole. The opposite gage 386 has a slide portion 398 and an upwardly projecting portion similar to the gage 384 formed on the end of the slide portion and carrying at its upper end a gage member provided with lower and upper lips 392, 394 and a sole engaging surface 396 of the same construction as the opposite gage. When the sole is lying flat on the pad the heel gages 384, 386 are in such a position relatively thereto that the projecting heel portion of the sole rests on the lower lips 392 of the gages, as indicated in broken lines in Fig. 16.

The slide portions of the heel gages are confined in the slot 382 by a cover plate 402 (illustrated in detail in Fig. 19) which is cut away at the proper places to permit widthwise sliding movement of the gages. The gages 384, 386 have projecting downwardly respectively from their lower sides pins 404, 406 between which extends a

relatively heavy tension spring 408, the spring passing through a hole 410 in the upper portion 380 of the arm 378. The spring 408 tends normally to urge the gages toward each other to bring their sole contacting surfaces into engagement with the opposite edge faces of the sole supported by the lower lips 392.

Mounted in the central portion of the cover plate 402 is an upstanding shoulder screw 412 upon which is rotatably mounted a lever 414, hereinafter referred to as the heel gage actuating lever. The lever 414 has pivotally secured to it at opposite sides of the center 412 a pair of curved links 416 and 418, best shown in Fig. 15, these links being secured respectively to the lever by screws 420, 422. The opposite end of the link 416 is secured by a pin 424 to the slide portion 388 of the right-hand sole gage 384 and the link 418 is secured by a pin 426 to the slide portion of the left-hand gage 386. Pivotal movement of the gage actuating lever 414 in a clockwise direction, as viewed in Fig. 15, will separate the gages into their open or retracted position and reverse movement of the lever will permit them to close yieldingly upon a sole through the action of the spring 408, as will be explained more fully hereinafter. The lever 414 has an upwardly projecting lug or ear 428 at its forward end in the upper portion of which is threaded a screw 430 (Fig. 15) which projects forwardly beyond the lug.

Rotatably mounted on the shoulder screw 412, above the lever 414, is another lever 432, hereinafter referred to as the gage locking lever, having a forwardly extending arm (Fig. 15) the outer portion of which is in the form of an upstanding block 434. When the gages are retracted, as shown in Figs. 15 to 18, inclusive, the projecting portion of the screw 430 engages the adjacent side of the block 434 and acts as a stop to determine the positions of the two levers relatively to each other about the pivot 412. A relatively light compression spring 436 surrounds the screw 430 between the ear 428 and the block 434, as best shown in Fig. 15, and, when the mechanism is positioned as illustrated in that figure the spring 436 is under a light compression.

The lever 432 has a rearwardly extending arm to which is pivotally secured by a screw 437 a link 438 secured at its opposite end by a screw 440 to a laterally extending arm 442 of a locking member 444 rotatably mounted on a pin 446 and having an eccentric portion 448 (Fig. 15) arranged, when the locking lever 432 is swung in a counterclockwise direction, to engage a finished surface on an upstanding projection 450 formed on the rear portion of the cover plate 402. When the eccentric 448 engages the projection 450 it jams and prevents the spring 408 from moving the gages further inwardly toward the sole, thereby locking the gages in operative position.

The block 434 on the gage locking lever 432 is connected by a universal joint arrangement 452, including a spring 453, to the upper end of an arm 454 of a bell crank lever pivotally mounted at its lower end on a pin 456 (best shown in Figs. 1, 2 and 15) carried by a boss in the lower portion of the gage supporting arm 378. The bell crank lever has a lower laterally extending arm 458 which carries on its outer end a roll 460. The arm 454 of the bell crank lever is normally maintained in an upstanding position, as shown in Figs. 2, 5 and 15, to hold the gage mechanism in an open or retracted position against the tension of the spring 408 by contact of the roll 460 with a lug 462 (Figs. 1 and 2) mounted on further mech-

anism, presently to be described, the lug bearing against the roll and expanding the spring 408. When the weight of the mechanism referred to is removed from the roll 460, the spring 408 moves 5 the heel gages yieldingly into engagement with the opposite edge faces of the heel portion of the sole. When the gages meet the opposite edge faces of the sole the light spring 436 between the gage actuating lever 414 and the lock operating lever 432 expands to force the lock operating lever further 10 in a counterclockwise direction, as viewed in Fig. 15, to operate the lock 448 and thereby to lock the gages against further movement toward the sole. Downward pressure on the roll 460 moves the arm 454 toward the left, as viewed in Fig. 15, first to bring the block 434 against the 15 end of the screw 430 and thereby unlock the gages, and thereafter to move the levers 414, 432 as a unit in a clockwise direction against the force of the spring 408 to open the gages to their retracted positions.

The mechanism for causing the heel gages to operate in a manner just explained and for causing shank and heel portions of the sole to be properly positioned widthwise relatively to the shoe bottom, and also for supporting the heel portion of the shoe against upward pressure from the movable portion of the pad will now be explained.

Pivotedly mounted on the transverse shaft 364 (Figs. 1 and 2), at opposite sides of the pad elevating lever 366, is a pair of forwardly and downwardly extending arms 464 (Figs. 1, 2 and 5) having pivotally mounted near their forward ends on pins 466 a pair of substantially triangular plates 468, each provided at its upper portion with a projection or arm 470. Pivotedly mounted on studs 472 in the ends of the arms 470 is a combined shoe engaging and last supporting member 474 which, as shown in Figs. 1, 2, 5 and 6, has a substantially V-shaped shoe engaging portion 476, a projection or lip 478 overhanging the V-shaped portion, and a downwardly curved arm 480 which provides a handle for grasping the positioning member and moving it into a position to find and embrace the heel portion of the shoe and also to engage and rest upon the heel portion of the last in the shoe. The inner sides of the two triangular plates 468 are finished surfaces and have a sliding fit with finished surfaces 482 (Figs. 1 and 5) on the opposite sides of the heel gage supporting lever 378. The lug 462 which engages the roll 460 of the bell crank lever above referred to is secured to the inner side of the left-hand plate 468, as viewed from the front of the machine. The last supporting and shoe engaging mechanism just described is arranged to be moved manually into operative position. Since it can be swung laterally of the shoe about the center 360 (Figs. 1 and 2), and can swing heightwise during such lateral movement about the centers 364 and 376, it will be seen that the combined shoe gage and last support 474 can be readily moved into any position necessary to contact the heel end of the last and shoe. Moreover, since 60 the heel sole gage mechanism is mounted on the arm 378 which, in turn, is pivoted to the lever 366, which is also arranged for lateral swinging movement about the center 360, any widthwise movement of the member 474 will impart a corresponding lateral movement of the mechanism which supports the heel sole gages, although this latter mechanism at that time will not be moved heightwise of the pad as will the shoe gage and last support through manual operation by the operator.

As stated above, after the operator moves the shoe engaging member or gage and last support 474 into operative position, as shown in Fig. 2, thereby positioning the heel end sole gage mechanism (which is then gripping the sole) laterally with respect to the rear portion of the shoe, the last support becomes locked against heightwise movement so that the shoe will be supported against pressure from the shank portion of the pad. The locking of the last support takes place 10 automatically during the operation of the mechanism for moving the shank portion of the pad against the shoe bottom.

In order to move the movable section 48 and the pad toward the shoe bottom the lever 366 is 15 swung upwardly about the pivot 364 by a treadle, the lever 366, of course, and the sole gages having been first swung laterally about the center 360 with the last and shoe engaging member 474 as previously explained. Pivotedly connected to 20 the lever 366 by the pin 376 is a downwardly extending bar 484, which may be conveniently termed the pad elevating bar and which, at its lower end, is pivotally connected to a bell crank lever 486 by a pin 488, the pin being loose in the 25 bar (as shown in Fig. 2) to permit the latter to swing laterally of the pad with the lever 366 without affecting the bell crank lever 486. The bell crank 486 is pivotally secured in the frame 38 on a pin 490 and has an upwardly extending arm 30 492 carrying a pin 494 which extends through a slot 496 formed in a downwardly extending link 498 provided at its lower end with another slot 499 through which passes a pin 500 mounted in the frame 32 (Figs. 2 and 3). The bell crank 35 lever 486 has a rearwardly projecting arm 502 which is pivotally connected by a pin 504 to a treadle rod 506 which, in turn, is pivotally secured at its lower end (Fig. 1) by a pin 508 to a treadle 510 pivoted on the shaft 60 and normally 40 held in an elevated position by a heavy spring 511 (Figs. 1 and 5). Depression of the treadle 510 swings the bell crank lever 486 in a clockwise direction, as viewed in Fig. 1, to move the bar 484 upwardly and thereby to cause the pad supporting lever 366 and the gage supporting lever 378 to move the pad and gages upwardly and thus bring the sole supported thereby against the bottom of the shoe, as shown in Fig. 2.

The arms 464 on the transverse shaft 364 have 50 forwardly extending portions 512 connected together by a transverse pin 514. Loosely mounted on this pin by an enlarged hole (Fig. 2) is a downwardly and rearwardly extending bar 516 which extends through a casting 518 pivotally mounted 55 between the frame members 32, 34 by the pin 500 and by a second pin 520 (Fig. 3), these pins being secured in the frame by set screws 522. The lower portion of the bar 516 has ratchet teeth 524 formed thereon, as shown in Figs. 1 and 2, and is 60 reduced in size to form a shoulder 526 about midway of its length. When the shoe gage and last support 474 and the mechanism associated therewith are located in an inoperative position, as shown in Fig. 1, the shoulder 526 rests against the top of the casting 518 thereby determining the inoperative position of the arms 464. Since the triangular plates 468 are pivoted at 466 on these arms 464 they will normally drop forwardly and downwardly away from the pad. The limit of 70 their downward swinging movement about the pins 466 is determined by adjustable stop screws 528 in lugs on the arms 464 and arranged to engage lugs 530 formed on the lower ends of the triangular plates 468.

The casting 518 has rearwardly projecting ears 534 between which is pivotally mounted on a pin 536 a pawl 538 having an upwardly projecting tail 540 (Fig. 2) engaged by a roll 542 mounted on the link 498. The position of the link 498 normally holds the roll 542 against the tail 540 of the pawl 538 and thereby keeps the pawl out of engagement with the ratchet teeth on the bar 516 against the action of a spring 544, connected at one end to the pawl and at its other end to the casting 518. Release of the pawl permits it to engage the teeth 524 and thereby to lock the bar 516 and all the mechanism supported thereby in any position into which the mechanism may have been moved while the pawl was held inoperative. The roll 542 is normally held positively against the pawl 538 by the bell crank lever 486 forcing the pin 494 against the lower end of the slot 496 in the link 498, as shown in Fig. 1, the bell crank lever, of course, being maintained in its inoperative position by the elevated treadle and its spring 511. Consequently, when the treadle 510 is depressed to rotate the arm 492 in a clockwise direction, as viewed in Figs. 1 and 2, the slotted link 498 is moved upwardly by the tail of the pawl 538 under the action of the spring 544 in pulling the pawl into engagement with the teeth 524. The slot 496 is long enough so that after the locking mechanism has operated, as shown in Fig. 2, the pin 494 still has clearance in the upper slot 496 to permit continued rotation of the bell crank lever 486 in elevating the pad and gage mechanism for a shoe having a relatively steep arch.

As indicated above, the sole gage mechanism may be adjusted heightwise of the supporting lever 378 to adapt it for operating on shoes having extremely high arches or, if desired, for operating on soles which have been preconformed to the shape of a last. This adjustment is readily accomplished by making the top portion 380 of the gage supporting lever separate from the lower portion 378 and securing these two members together by any usual means such, for example, as a screw 546 (Figs. 1 and 2), the contacting surfaces of the two portions of the lever being preferably corrugated horizontally so that they will interlock in adjusted position.

In order to maintain the gage supporting lever 378 in an upwardly extending position, that is, to prevent it from swinging forwardly about its pivot 376 the following mechanism is provided. An arm 548 is pivoted on the pin 376 and extends upwardly behind the gage supporting lever 378, as viewed in Figs. 1 and 2. The upper end of the arm 548 has a finished surface 550 (Fig. 2) which is arranged to bear and ride on the front end of the pad supporting section 48. The arm 548 is held inwardly to keep the surface 550 against the section 48 by a tension spring 552 secured at one end to the arm and at its other end to a pin 554 mounted in the pad supporting lever 366. About midway of its length the arm 548 is provided with a laterally projecting pin 556 through which is threaded a forwardly extending rod 558, the forward portion of the rod passing loosely through another pin 560 on the gage supporting lever 378. The rod 558 has a shoulder 561 thereon against which the pin 560 is caused to bear by a compression spring 562 extending between the two pins 556, 560 and holding the arm 548 and lever 378 separated from each other. The forward end of the rod 558 is provided with a hand wheel 564 whereby the rod may be adjusted forwardly and rearwardly relatively to

the arm 548 to move the gage supporting lever 378 and the heel gages toward and away from the movable section 48 of the pad support. In this way the gages may be moved as a unit lengthwise of the shoe until they are positioned to engage the projecting heel portion of the sole at the desired location lengthwise, this position preferably being near the widest part of the heel end of the sole. The spring 552, of course, yields to allow for the swing of the section 48 as it is moved toward and away from the shoe bottom.

In the operation of the machine the operator places a sole A on the pad 46 while the latter is flat, as shown in Fig. 1, the projecting heel portion of the sole resting loosely on the heel gages 384, 386. He then depresses the treadle 58 to move the forepart sole and shoe gages inwardly toward each other until the sole gages find the opposite edge faces of the sole and become locked in such position. During this operation the forepart holdown or presser foot 270 has been moving toward the pad. After the forepart gages have become locked the operator removes his foot from the treadle which, through the lock 290, 292 (Fig. 1), remains in this depressed position, and he places a shoe B on a last L on the forepart of the sole in the position determined by the locked shoe gages, as shown in Fig. 2. The operator then completes the depression of the treadle 58 to bring the presser foot 270 into engagement with the forepart of the shoe and press it and the sole firmly against the fixed portion 44 of the pad, the presser foot remaining in such position because the treadle becomes locked again when the operator completes its depression. The operator next grasps the handle 480 of the heel gage and last supporting mechanism and swings the heel gage 476 upwardly and as much laterally as is necessary to cause it to embrace the heel end of the shoe and to cause the support 478 to rest on the heel end of the last. In doing this the operator has moved the heel sole gage mechanism laterally with the shoe gage by reason of the triangular plates 568 contacting with the gage supporting lever 378 and the mechanism associated therewith. Consequently, the sole and shoe are now positioned laterally throughout their entire areas, the shank and heel portions of the sole, if necessary, having been moved relatively to the forepart by the foregoing action while the sole was still resting flat on the pad so that it was spaced from the shoe bottom during the positioning operation.

The operator depresses the pad elevating treadle 510 which first frees the locking pawl 538 (Fig. 2) and causes it to lock the bar 516 against further upward movement, thereby locking the last support 478 in operative position. Immediately thereafter the pad elevating bar 484 and lever 366 swing upwardly about the pivot 364 to swing the pad supporting section 48 and the movable portion of the pad 46 about the center 50 and thereby to bring said portion and the shank portion of the sole A forcibly against the shoe bottom and apply pressure to the shank portion of the shoe bottom. The operator may then release the treadle 510 which permits the movable portion of the pad and its supporting mechanism to swing downwardly away from the shoe and in so doing to release the locking pawl 538 so that the bar 516 is free to descend after the last support and shoe gage 474 have swung outwardly away from the

last and shoe, this action occurring almost instantly. As the last support and shoe gage swing outwardly and downwardly into inoperative position about the pivot 466, the lug 462 (Figs. 1 and 2) engages the roll 460 on the bell crank lever 454 and thereby operates the sole gage locking and actuating levers (Figs. 15 to 18, inclusive) to withdraw the heel gages from the edge face of the sole positively against the spring 408. The heel ends of the sole and shoe are now entirely free from the last support and the shoe and sole heel gages and the shank portion of the shoe is free from the pressure of the movable shank portion of the pad which has now returned to its normal position in the same plane as the fixed portion. The operator next actuates the treadle release 300 to permit the locked treadle 58 to return to its elevated position and, through the various connections previously described, to unlock and withdraw the forepart sole and shoe gages and return the presser foot 210 to its inoperative position, thereby permitting removal of the shoe with the sole properly positioned and temporarily attached or spotted on the shoe bottom. The mechanisms of the machine are so constructed and arranged that the entire operation of spotting the sole on the shoe bottom may be performed quite rapidly since the timing is such that the various functions of the several mechanisms occur in very close sequence. Accordingly, the operator may present to the machine soles and shoes which have been previously treated with cement at their marginal portions for permanently attaching the sole to the shoe bottom such, for example, as pyroxylin cement, and have preferably, but not necessarily, been spotted at their central portions with an initially tacky or quick setting cement, and he may operate on these shoes in rapid succession. The only adjustment he will have to make for a quantity or lot of shoes ranging from large to small sizes will be the adjustment provided for varying the positions of the ball line shoe gages relatively to their sole gages for operating successively on right and left shoes. Since this adjustment is quickly made by swinging the lazy tong mechanism from one position to another by the nut or handle 328, practically no time is lost in operating successively on right and left shoes. When the sole extension of a pair of shoes varies from those previously operated upon, or when the arc in the shank portion of a shoe is extremely high or low so that it is outside the range that the machine has been set to accommodate, the other adjustments referred to may be made.

After the shoes have had their outsoles properly positioned and spotted by the present machine they may be placed immediately in a sole attaching press of any usual or conventional type and have the outsoles permanently attached by holding the shoes under relatively heavy pressure while the sole attaching cement is setting. If desired, the shoes may be stacked in a rack after the soles have been spotted by the present machine and, when the rack is full, it may be moved to a multiple station cement sole attaching machine in which the soles may be permanently attached. This is possible because the speed with which the present machine can be operated is such that a comparatively large number of shoes can have their soles spotted before the slower setting sole attaching cement can set sufficiently to interfere with the sole attaching operation.

Having thus described my invention, what I

claim as new and desire to secure by Letters Patent of the United States is:

1. A machine for pressing soles on shoe bottoms having, in combination, a pad for receiving a sole and shoe, said pad having a fixed portion and a portion movable in an arc relatively to said fixed portion, said portions being initially located in the same plane, means for pressing the forepart of the shoe against said fixed portion of the pad, means for swinging said movable portion in an arc to press it against the shank portion of the shoe irrespective of the shape of the shoe, means for engaging the heel portion of a last in the shoe and supporting the rear portion of the shoe against the pressure from said movable portion of the pad, and means operated by movement of the movable portion of the pad into pressure applying position for locking the shoe supporting means against movement heightwise of the shoe in response to pressure from said movable portion. 20

2. A machine for pressing soles on shoe bottoms having, in combination, a pad for receiving a sole and shoe, said pad having a fixed portion and a movable portion both lying initially in the same plane, means for pressing the forepart of the shoe against the fixed portion of the pad, means for locking said pressing means in operative position, treadle operated means for moving said movable portion of the pad out of said plane and into pressure applying relation with the shank portion of the shoe irrespective of the shape of said shank portion, a member movable into operative position by an operator for supporting the rear portion of the shoe against pressure on its shank portion, a pawl for locking said supporting member in operative position, and means for automatically releasing said pawl to unlock said supporting member after pressure has been applied to said shank portion. 35

3. A machine for pressing soles on shoe bottoms having, in combination, a pad for receiving a sole and shoe, means for pressing the forepart of the shoe against the pad, means for maintaining the pressure on said forepart, means for moving the pad against the shank portion only of the shoe irrespective of its shape to apply pressure thereto, means for supporting the rear portion of the shoe against the pressure at its shank portion, said means being movable in all directions to engage the last in said shoe, and means operated by movement of the pad into pressure applying relation with the shank portion of the shoe for locking said supporting means against movement heightwise of the shoe during the application of pressure to said shank portion. 55

4. A machine for pressing soles on shoe bottoms having, in combination, a pad for receiving a sole and a lasted shoe, means for engaging the last in the shoe and supporting the shoe against pressure from the pad, and means operated by movement of said supporting means into operative position for engaging the sole and positioning it relatively to the shoe bottom. 60

5. A machine for pressing soles on shoe bottoms having, in combination, a pad for receiving a sole and shoe, means movable in all directions for supporting the heel portion of the shoe against pressure from the pad, and means operated by movement of said supporting means into shoe supporting position for engaging the heel portion of the sole and positioning it relatively to the shoe bottom. 70

6. A machine for pressing soles on shoe bottoms having, in combination, a pad for receiving a sole and shoe, means for finding the heel portion of the shoe and supporting it against pressure from the pad, and gages operated by movement of said shoe finding means into operative position for engaging the opposite edge faces of the heel portion of the sole and positioning it laterally relatively to the heel portion of the shoe. 5
7. A machine for pressing soles on shoe bottoms having, in combination, a pad for receiving a sole and shoe, means for supporting the shoe against pressure from the pad, and gages operated by movement of said supporting means into operative position for engaging the opposite edge faces of the sole and positioning the sole laterally relatively to the shoe bottom, said gages being movable in paths located substantially at right angles to the edge faces of the sole. 10
8. A machine for pressing soles on shoe bottoms having, in combination, a pad for receiving a sole and shoe, means for supporting the shoe against pressure from the pad, gages for engaging the opposite edge faces of the sole and positioning the sole relatively to the shoe bottom, and means for locking the gages against movement toward the sole after each gage has contacted with the sole, said gages and said locking means being operated by movement of said supporting means into shoe supporting position. 15
9. A machine for pressing soles on shoe bottoms having, in combination, a pad for receiving a sole and shoe, means for clamping the foreparts of the sole and shoe on the pad in proper positions relatively to each other, means for effecting relative movement between the shoe and the shank portion of the pad to apply pressure to the shank portion of the shoe, means for finding the heel portion of the shoe, gages for engaging the heel portion of the sole and positioning it relatively to the shoe bottom, and means operated by movement of said shoe finding means into operative position for operating said gages. 20
10. A machine for pressing soles on shoe bottoms having, in combination, a pad for receiving a sole and shoe, said pad having a fixed portion and a movable portion both lying initially in the same plane, means for moving the movable portion of the pad out of said plane to apply pressure to the shoe bottom, and gages carried by said means for engaging the sole and positioning it relatively to the shoe bottom before pressure is applied thereto. 25
11. A machine for pressing soles on shoe bottoms having, in combination, a pad for receiving a sole and shoe, said pad having a fixed portion and a movable portion, means for swinging said movable portion toward the shoe bottom irrespective of its shape to apply pressure to the sole and shoe, gages separate from the pad for positioning the sole relatively to the shoe bottom, and means for maintaining said gages in a predetermined relation to the movable portion of the pad in any position into which the latter may be swung. 30
12. A machine for pressing soles on shoe bottoms having, in combination, a pad for receiving a sole and shoe, said pad having a fixed portion and a movable portion, means for swinging said movable portion toward the shoe to apply pressure to the sole and shoe, gages movable in paths located substantially at right angles to the opposite edge faces of the sole for positioning it relatively to the shoe, means separate from the pad for supporting said gages in a predetermined position relatively to the movable portion of the pad, and means for operating the gages in any position in which they may be located after the movable portion of the pad has been swung toward the shoe bottom. 5
13. A machine for pressing soles on shoe bottoms having, in combination, a pad for receiving a sole and shoe, said pad comprising a fixed portion and a movable portion, means for swinging said movable portion toward the shoe bottom to apply pressure to the sole and shoe, gages for positioning the sole on said movable portion relatively to the shoe, said gages being arranged to engage the sole before the movable portion is swung toward the shoe, means for finding the shoe, said means being arranged also to cause the sole gages to engage the sole and thereafter to align said gages relatively to the shoe bottom, thereby positioning the sole relatively to the shoe, and means for maintaining the gages in a predetermined position relatively to the movable portion of the pad as it is swung toward the shoe bottom. 10
14. A machine for pressing soles on shoe bottoms having, in combination, a pad for receiving a sole and shoe, said pad having a fixed portion and a movable portion, means for pressing the forepart of the shoe against said fixed portion, means for moving said movable portion against the shank portion of the shoe, means for supporting the shoe against pressure from said movable portion, gages movable in opposite directions for engaging the opposite edge faces of the heel portion of the sole and positioning said portion relatively to the shoe bottom, and means for operating said gages yieldingly, said means operating automatically during movement of said shoe supporting means into operative position. 15
15. A machine for pressing soles on shoe bottoms having, in combination, a pad for receiving a sole and shoe, said pad having a fixed portion and a movable portion both lying initially in the same plane, means for pressing the forepart of the shoe against the fixed portion of the pad, a lever movable about axes located at right angles to each other for moving the movable portion of the pad against the shank portion of the shoe, thereby applying pressure to said shank portion, gages carried by said lever and bearing a predetermined relation to the movable portion of the pad for engaging the opposite edge faces of the heel portion of the sole and positioning it relatively to the shoe bottom, means for supporting the rear portion of the shoe against pressure from the movable portion of the pad, and means operated by movement of said shoe supporting means into operative position for operating said gages before the movable portion of the pad has moved against the shank portion of the shoe. 20
16. A machine for pressing soles on shoe bottoms having, in combination, a pad for receiving a sole and shoe, a separate set of sole and shoe gages at each side of the pad for positioning the sole and shoe relatively to each other at the ball lines of the sole and shoe, cams for relatively adjusting the gages of each set to adapt them for alternatively positioning on the pad right and left shoes in which the greater extension of the sole beyond the shoe bottom is located re- 25

spectively at opposite sides of the pad, and means for simultaneously operating said cams.

17. A machine for pressing soles on shoe bottoms having, in combination, a pad for receiving a sole and shoe, gages at opposite sides of the pad for relatively positioning a sole and shoe thereon, said gages being constructed and arranged to slide in straight paths toward and away from the sole and shoe and to control the extension of the sole beyond the shoe bottom, and means for simultaneously varying the initial relative positions of the gages in their paths at opposite sides of the pad to adapt said gages for operating successively on shoes the soles of which have a greater extension on one side of the shoe than on the other, irrespective of which side of the shoe has the greater sole extension.

18. A machine for pressing soles on shoe bottoms having, in combination, a pad for receiving a sole and shoe, gages for positioning the sole and shoe relatively to each other, thereby determining the extension of the sole beyond the shoe upper at opposite sides of the shoe, and cams for adjusting said gages to adapt them for operating successively on shoes in which the sole has a greater extension on one side of the shoe than on the other and which greater extension is located alternatively on opposite sides of the pad in successive shoes.

19. A machine for pressing soles on shoe bottoms having, in combination, a pad for receiving a sole and shoe, sole and shoe gages arranged to engage opposite sides of the sole and shoe and position them relatively to each other, said gages thereby determining the extension of the sole edge beyond the shoe upper, and means for simultaneously changing the initial positions of the shoe gages at opposite sides of the shoe relatively to their respective sole gages thereby to adapt the gages for operating on shoes in which the sole extension is greater at one side of the shoe than at the other but which greater extension is located at opposite sides of the shoe in successive shoes, said means including cams acting only on the shoe gages.

20. A machine for pressing soles on shoe bottoms having, in combination, a pad for receiving a sole and shoe, sole and shoe gages for engaging a sole and shoe at opposite sides of the ball line of the shoe and positioning them relatively to each other, said gages being arranged to control the extension of the sole beyond the shoe upper at said ball line, cams for simultaneously adjusting the shoe gages at opposite sides of the ball line relatively to their corresponding sole gages the same amount and in the same direction widthwise of the shoe, a shaft for supporting said cams, and means for rotating said shaft.

21. A machine for pressing soles on shoe bottoms having, in combination, a pad for receiving a sole and shoe, sole and shoe gages located at opposite sides of the pad for positioning the sole and shoe relatively to each other and for determining the extension of the sole relatively to the shoe bottom, means for operating said gages yieldingly, and means independent of said operating means for changing the positions of the shoe gages relatively to the sole gages at opposite sides of the pad equal amounts in the same direction to adapt the gages for operating successively on right shoes having a greater sole extension on the right-hand side of the shoe, and on the left shoes having a greater sole extension on the left-hand side of the shoe.

22. A machine for pressing soles on shoe bot-

toms having, in combination, a pad for receiving a sole and shoe, sole and shoe gages slidably at opposite sides of the pad substantially at right angles to the edge of the sole for positioning the sole and shoe relatively to each other and for determining the extension of the sole relatively to the shoe bottom, levers for sliding said sole and shoe gages toward and away from the sole and shoe and for controlling the positions of the shoe gages relatively to the sole gages, and means carried by the sole gage operating levers for simultaneously changing the positions of the shoe gage operating levers at opposite sides of the pad relatively to the positions of the sole gage operating levers to adapt the sole and shoe gages for operating successively on right and left shoes, said means being independent of said shoe gage operating levers and their gage operating functions.

23. A machine for pressing soles on shoe bottoms having, in combination, a pad for receiving a sole and shoe, sole and shoe gage mechanisms located at opposite sides of the pad for positioning the ball line portions of the sole and shoe relatively to each other and for determining the overhang of the edge portion of the sole relatively to the shoe bottom at opposite sides of the shoe, levers connected to each of said gages, springs for operating said levers as a unit to cause the gages to move yieldingly into operative position, and means including cams for simultaneously varying the positions of the shoe gage levers at opposite sides of the pad relatively to their corresponding sole gage levers, thereby to adapt the sole and shoe gages for operating successively on right and left shoes in which the sole edge has a greater overhang at one side of the shoe than at the other, and which greater overhang is located at opposite sides of the pad.

24. A machine for pressing soles on shoe bottoms having, in combination, a pad for receiving a sole and shoe, gage mechanisms for positioning the foreparts of the sole and shoe relatively to each other on the pad, said mechanisms being arranged to operate on opposite sides of the tip line of the shoe and on opposite sides of its ball line, means for operating said gage mechanism simultaneously, and means independent of said operating means for simultaneously adjusting the ball line gage mechanisms widthwise to adapt them for operating successively on right and left shoes in which the extension of the sole relatively to the shoe bottom is greater at one side of the shoe than at the other side, and which greater extension is located on opposite sides of the pad in right and left shoes.

25. A machine for pressing soles on shoe bottoms having, in combination, a pad for receiving a sole and shoe, gage mechanisms for positioning the foreparts of the sole and shoe relatively to each other on the pad, said mechanisms being arranged to operate on opposite sides of the tip line and the ball line of the shoe, means for simultaneously adjusting the ball line gage mechanisms widthwise of the pad to adapt them for operating successively on right and left shoes in which the sole extensions are greater at the outsides of the shoes than at the insides, and which greater sole extensions are located on opposite sides of the pad, and means for relatively positioning the shank and heel portions of the sole and shoe, said means being movable widthwise of the pad in an arc struck approximately from the ball line of the shoe, thereby adapting said

means to be moved into any position for operating on either right or left shoes.

26. A machine for pressing soles on shoe bottoms having, in combination, a pad for receiving a sole and shoe, gage mechanisms for positioning the foreparts of the sole and shoe relatively to each other on the pad, said mechanisms being arranged to operate on opposite sides of the tip line of the shoe and on opposite sides of its ball line, means for simultaneously adjusting said ball line gage mechanisms widthwise of the pad to adapt them for operating successively on right and left shoes in which the sole extensions are greater at the outsides of the shoes than at the insides and which greater extensions are thus located on opposite sides of the pad, a member for finding the heel portion of the shoe, and gages for positioning the heel portion of the sole relatively to the shoe, said shoe finding member and sole gages being arranged to swing widthwise of the pad about an axis located substantially at the ball line of the shoe thereby to adapt the gages for operating on either right or left shoes.

27. A machine for pressing soles on shoe bottoms having, in combination, a pad for receiving a sole and shoe, sole and shoe gages for positioning the sole and shoe relatively to each other on the pad, said gages being arranged to operate on the sole and shoe at opposite sides thereof, means for simultaneously moving the shoe gages at opposite sides of the shoe relatively to the sole gages to adapt said gages for operating successively on right and left shoes, said means being rotatable about an axis extending widthwise of the pad, and means for adjusting the shoe gage moving means to limit its rotation about said axis and thereby to vary the amount of the simultaneous movement of said shoe gages.

28. A machine for pressing soles on shoe bottoms having, in combination, a pad for receiving a sole and shoe, sole and shoe gages for positioning the sole and shoe relatively to each other on the pad, said gages being arranged to operate on the sole and shoe at opposite sides thereof, cams for simultaneously adjusting the shoe gages at opposite sides of the shoe widthwise relatively to the sole gages to adapt the sole and shoe gages for operating alternatively on right and left shoes which have a greater sole extension on their outer sides than on their inner sides, which greater extensions are located on opposite sides of the pad in right and left shoes, and manually controlled means for varying the operative movements of said cams and thereby to control the amount of the widthwise adjustment of said shoe gages.

29. A machine for pressing soles on shoe bottoms, having, in combination, a pad for receiving a sole and shoe, separate sets of sole and shoe gages for positioning the sole and shoe relatively to each other, said sets being located at opposite sides of the shoe, manually operated means rotatable about a horizontal axis for shifting the shoe gages at opposite sides of the shoe widthwise as a unit relatively to the sole gages to adapt the gages for operating selectively on right and left shoes, a stop for limiting the rotating movement of said manually operated means, and means carried by said manually operated means for varying the rotating movement relatively to said stop and thereby varying the amount that the shoe gages may be shifted as a unit by said manually operated means.

30. A machine for pressing soles on shoe bottoms having, in combination, a pad for receiving

a sole and shoe, separate sets of sole and shoe gages for positioning the sole and shoe relatively to each other, said sets being located at opposite sides of the tip line and the ball line of the shoe, means for operating said gages simultaneously to find the edge faces of the sole on the pad, means for moving the ball line shoe gages as a unit widthwise of the pad relatively to their sole gages to adapt these sets of gages for operating successively on right and left shoes, said means operating independently of the gage operating means, and means also independent of said gage operating means for varying at will the amount of widthwise movement of said ball line shoe gages relatively to their sole gages.

31. In a machine for pressing soles on shoe bottoms, a sole gage and a shoe gage for relatively positioning a sole and shoe to be operated upon, a lever connected to each gage, a spring acting on one of said lever to force the gage connected thereto toward the sole and shoe, mechanism acting on said last-named lever against the spring to hold its gage normally away from the sole and shoe, manually operated means for releasing said mechanism to permit the spring to operate, and connections between said levers whereby the spring actuated lever moves the other lever positively toward the shoe and yieldingly away from the shoe.

32. In a machine for pressing soles on shoe bottoms, a sole gage and a shoe gage arranged to position a sole and shoe to be operated upon relatively to each other, a lever connected to each of said gages, a spring acting on the sole gage lever to force it toward the sole, mechanism acting against said spring to hold the sole gage lever away from the sole, connections between said levers whereby movement of the sole gage lever toward the sole moves the shoe gage lever positively an equal amount toward the shoe, and means for maintaining said levers normally in the same positions relatively to each other.

33. In a machine for pressing soles on shoes bottoms, a sole gage and a shoe gage arranged to position a sole and shoe to be operated upon relatively to each other, a lever connected to each of said gages, a spring acting on the sole gage lever to force it toward the sole, treadle operated mechanism acting against said spring to hold the sole gage lever away from the sole, connections between said levers whereby movement of the sole gage lever toward the sole moves the shoe gage lever positively an equal amount toward the shoe, means for normally maintaining said levers in the same positions relatively to each other, and manually operated means for varying said positions to change the relative positions of the gages.

34. In a machine for pressing soles on shoe bottoms, a sole gage and a shoe gage arranged for sliding movement toward and from a sole and shoe to position them relatively to each other, a spring for moving said gages yieldingly into operative position, means for locking said gages against further sliding movement toward the sole and shoe, and separate means actuated by engagement of the sole gage with the sole for automatically operating said locking means.

35. In a machine for pressing soles on shoe bottoms, a sole gage and a shoe gage for relatively positioning a sole and shoe, levers for operating said gages, a spring acting on the sole gage lever to move its gage toward a sole to be operated upon, connections between said sole gage lever and the shoe gage lever for causing

the latter to move toward the sole as a unit with the sole gage lever, means for locking said gages against further movement toward the sole, a third lever for operating said locking means, and connections between said third lever and said sole gage lever for causing the third lever to operate the locking means upon engagement of the sole gage with the sole.

36. In a machine for pressing soles on shoe bottoms, a sole gage and a shoe gage, levers connected to said gages for moving them toward and away from a sole to be operated upon, a cam carried by the sole gage lever, a spring between said levers holding the shoe gage lever against the cam, thereby determining the positions of said levers and gages relatively to each other, a spring for moving said levers toward the sole, means for swinging the levers to move the gages away from the sole, and means independent of said spring and said moving means for changing the position of said cam and thereby varying the positions of the levers and the gages relatively to each other.

37. In a machine for pressing soles on shoe bottoms, a sole gage and a shoe gage arranged for sliding movement toward and from a sole and shoe to position them relatively to each other, levers connected to said gages, connections between said levers causing them to operate as a unit, a spring for swinging said levers to move the gages toward the sole and shoe, a third lever, means operated by said third lever for locking all said levers in operative position, and connections between said third lever and the sole gage lever whereby said third lever operates the locking means upon engagement of the sole gage with the sole and releases said locking means before movement of the sole gage away from the sole.

38. In a machine for pressing soles on shoe bottoms, a sole gage and a shoe gage for relatively positioning a sole and shoe and arranged for sliding movement toward and away from the shoe, levers connected to said gages and fulcrumed on a common axis, a third lever fulcrumed on said axis, a spring normally urging the sole gage lever toward the sole, connections between the shoe gage lever and the sole gage lever whereby movement of the latter toward the sole moves the shoe gage lever positively an equal distance toward the shoe, and whereby movement of the sole gage lever away from the sole moves the shoe gage lever yieldingly away from the shoe, treadle operated mechanism normally holding said third lever away from the sole and shoe, means between said third lever and said sole gage lever whereby operation of said treadle operated mechanism causes said sole gage lever to move said third lever positively toward the sole, means for locking the gages against movement relatively to the sole and shoe, and further means between said sole gage lever and said third lever for causing said third lever to operate said locking means automatically when the sole gage engages the sole.

65 39. In a machine for pressing soles on shoe bottoms, a pair of gages for positioning an end portion of a sole relatively to a shoe bottom, a spring for operating said gages, a lever connected to both gages for retracting them against said spring, and means engaging said lever and movable relatively thereto for locking said gages upon their contact with the sole.

70 40. In a machine for pressing soles on shoe bottoms, a pair of gages for positioning an end portion of a sole relatively to a shoe bottom, a

spring for operating said gages, a lever connected to both gages for retracting them against said spring, a lock for said gages, a lever for actuating said lock, and means for causing said lock actuating lever to operate automatically when the gages contact with the sole.

41. In a machine for pressing soles on shoe bottoms, a pair of gages for positioning an end portion of a sole relatively to a shoe bottom, a spring for operating said gages, a lever connected to both gages for retracting them against said spring, an eccentric lock for said gages, a lever for actuating said lock, and mechanism between the gage retracting lever and the lock actuating lever for maintaining the lock inoperative during the movement of the gages into engagement with the sole and for thereafter operating said lock.

42. In a machine for pressing soles on shoe bottoms, a pair of gages for positioning the heel portion of a sole relatively to a shoe, said gages being arranged to slide equal amounts in opposite directions into and out of operative position, an eccentric lock carried by one of said gages for locking them in operative position, and means actuated independently of said gages for operating the lock automatically after both gages have contacted with the sole.

43. In a machine for pressing soles on shoe bottoms, a pair of gages for positioning the heel portion of a sole relatively to a shoe, said gages being arranged to slide equal amounts in opposite directions toward and from the sole, eccentric means carried by one of said gages for locking them both against movement away from the sole, a fixed surface co-operating with said eccentric locking means, a lever for operating said locking means, and a spring normally under compression for actuating said lever automatically when both gages have contacted with the sole.

44. In a machine for pressing soles on shoe bottoms, a pair of gages for positioning the heel portion of a sole relatively to a shoe, said gages being arranged to slide equal amounts in opposite directions toward and from a sole to be operated upon, eccentric means carried by one of said gages for locking them both against movement away from the sole after they have contacted therewith, a fixed surface co-operating with said eccentric means in locking the gages, a lever for operating said eccentric means, a spring normally under compression for swinging said lever in one direction relatively to the gages after both gages have contacted with the sole, thereby operating the eccentric locking means, and means for swinging the lever in an opposite direction to unlock the gages and compress the spring before the gages are retracted from the sole.

45. A machine for pressing soles on shoe bottoms having, in combination, a pair of gages for positioning a sole relatively to a shoe bottom, a spring for actuating said gages, mechanism for retracting the gages against said spring, and means for engaging the heel portion of the shoe, said means being constructed and arranged when in an inoperative position to hold the gages retracted.

46. In a machine for pressing soles on shoe bottoms, gages movable equal distances in opposite directions for positioning a sole relatively to a shoe bottom, a spring for actuating said gages, a lever connected to both gages for retracting them against the spring, a lock for said gages, a lever for operating said lock, means between the gage retracting lever and the lock operating lever for actuating the latter automatically to

operate the lock when the gages contact with the sole, and means for finding the heel portion of the shoe, said means acting when in an inoperative position to hold the gages retracted against their actuating spring.

47. In a machine for pressing soles on shoe bottoms, gages for positioning the heel portion of a sole relatively to a shoe, a spring for actuating said gages, means for retracting said gages against said spring, means for finding the heel end of a shoe, said means being movable from an outwardly inclined inoperative position into shoe engaging position, and connections between said shoe finding means and said gages whereby the gage retracting means is operated automatically

by movement of the shoe finding means into its outwardly inclined inoperative position.

48. In a machine for pressing soles on shoe bottoms, gages for positioning the heel portion of a sole relatively to a shoe bottom, a spring for actuating said gages, means for finding the heel portion of a shoe on the sole, and connections between said shoe finding means and the gages for permitting the spring to actuate the gages when the shoe finding means is operated, said connections also being caused to retract the gages automatically against said spring by return of the shoe finding means to inoperative position.

SIDNEY J. FINN. 15

CERTIFICATE OF CORRECTION.

Patent No. 2,168,475.

August 8, 1939.

SIDNEY J. FINN.

It is hereby certified that error appears in the printed specification of the above numbered patent requiring correction as follows: Page 2, second column, line 64, for the reference numeral "53" read --54--; page 5, second column, line 5, for "pay" read --pad--; page 13, second column, line 48, claim 24, for "mechanism" read --mechanisms--; page 14, first column, line 19, claim 26, for "filding" read --finding--; line 70, claim 29, for "the" read --its--; same page, second column, line 20, claim 31, for "lever" read --levers--; line 52, claim 33, for "mves" read --moves--; and that the said Letters Patent should be read with this correction therein that the same may conform to the record of the case in the Patent Office.

Signed and sealed this 4th day of June, A. D. 1940.

(Seal)

Henry Van Arsdale,
Acting Commissioner of Patents.
